NARROW WARE LOOM

Max Hahne, New York, N. Y.

Application June 20, 1946, Serial No. 678,111

10 Claims.

(Cl. 139—18)

1

This invention relates to looms, and more particularly to those of the jacquard type especially adapted for use in weaving narrow fabrics such as woven labels, trimmings and the like.

The primary object of the invention is to provide a loom of this character of simplified and lightweight construction; which will operate at high speed and with efficiency; which can be manufactured at much lower cost than the conventional looms in this category and which will nevertheless have greatly increased work output.

In addition to the advantages above enumerated, the invention contemplates the employment of a horizontally movable batten carrying a plurality of vertically movable shuttles, the latter being mounted for gravitational descent to carry the weft threads across the warp.

Another object of the invention is to provide in a loom of this character, means by which the fabric is woven with the plane of the produced fabric disposed vertically whereby gravity may be utilized to carry the shuttles downwardly to thereby insert the weft threads in the fabric.

Still another object of the invention is to provide a loom in which the operating parts are so arranged that a plurality of fabrics of similar design can be simultaneously woven while, at the same time, the loom will occupy a minimum of floor space.

These and other objects are attained by the structure hereinafter described and more particularly pointed out in the claims appended hereto.

In the accompanying drawings, forming a part hereof, Fig. 1 is a front elevation of a portion of a loom constructed in accordance with the invention;

Fig. 2 is an end elevation of the loom batten and associated parts;

Fig. 3 is a top plan view of the structure shown in Fig. 2;

Fig. 4 is a top plan view of one of the heddles; Fig. 5 is a side view of the heddle;

Fig. 6 is a sectional view on the line 6—6 of Fig. 1, looking in the direction of the arrows;

Fig. 7 is a front view of the fixed frame which supports the reed, showing also one of the fingers for operating the latches which release and allow gravitational descent of the shuttles; and

Fig. 8 is a transverse sectional view of the shuttle guides and the latch means thereon for holding the shuttles in their raised position.

The present invention relates particularly to the loom batten, the manner in which it is moved; to the shuttles and the means of operation of the same, and the novel manner by which the fabric

2

is woven with the plane of the fabric disposed vertically. Therefore, the accompanying drawings show the co-operating parts of the loom which carry out the means of operation of the above features.

The loom batten includes the beam 1, which is supported at its ends by the arms 2. Each arm 2 is pivotally attached at 4 to a lug 5 extending from the beam 1. The arm 2 is part of a bell crank lever arrangement which has a second arm 6 mounted to rock on shaft 7. A rod 8 extends to suitable cam or similar mechanism, the operation of which aids in causing descent of the shuttle push-rods to be described.

The batten frame is shown at 10, the same consisting of an elongated, substantially rectangular frame, clearly shown in Fig. 1, upon which a number of groups of shuttles 26 are carried. The loom shown is of the gang type, so that five fabrics can be simultaneously woven, each fabric, in the arrangement disclosed having weft threads of three colors inserted, there being three shuttles shown for each fabric. The batten frame 10 is mounted to have a longitudinal reciprocating movement along the top of the beam 1, by means of a suitable operating mechanism including the bell crank 11 having an arm 13 pivotally attached at 14 to one end of a link 15, which has its opposite end pivotally attached at 16 to the batten frame. The second arm of the bell crank is pivotally attached at 17 to a push-rod 18 extending from suitable cam or other mechanism acting to move the batten frame back and forth along the top of the beam 1 for a limited distance and in proper timing. To permit longitudinal movement of the batten 10 by means of mechanism above described, rollers 19 are carried by the batten, the same riding upon the suitable track surfaces 20 provided on the top of the beam 1.

Provided on the forward face of the upper bar 21 of the batten frame 10 are the upper shuttle guides 22 shown clearly in Figs. 6 and 8. Each guide is provided with the three channels 23, 24 and 25 in each of which a shuttle 26 is slidable.

The rear portion 27 of each shuttle 26 is in the form of a spur provided with an inclined cam surface 28 which, upon rising movement of the shuttle, acts to force a spring latch 29, having a part normally located in the channel of the shuttle guide, out of the way, to permit passage of the shuttle to enable it to reach its elevated position, as shown in Fig. 6. When the shuttle reaches said elevated position, the padded shoul-

der 30 on the lower end of the spur 27 of the shuttle, takes over a shoulder 31 on the latch 29 so that the latch then holds the shuttle in its raised position. Each of the shuttle guides 23, 24 and 25 is provided with one of the latches 29 so that when each shuttle is raised up in its upper guide it will be engaged by one of these spring-pressed latches 29 and be thus held in its raised position, and so maintained until released by means to be described. The latches 29 for each group of shuttle guides 22 are mounted on a shaft 32 at the back of the shuttle guides, said shaft being secured in the lugs 33 and 34. (See Fig. 8.) A torsional spring 35 tends to hold each latch forwardly and in position to have its shoulder 31 engage under the padded shoulder 30 of its shuttle 26 when the shuttle is raised to its elevated position.

The bottom shuttle guides are shown at 36, the same being arranged in groups of three and being secured on the lower bar 37 of the batten frame 10 directly below the upper shuttle guides 22. The bottom of the lower shuttle guides 36 is closed by a stop plate 38 lined with a pad 39 of soft material, such as felt. When the latches 29, or either of them, are released, they will free the shuttles 26 held by them, and the shuttles so released will descend by gravity and slide down in the lower shuttle guides 36, thus carrying their threads across the warp threads 40 extending through the reed 9 and positioned between the upper and lower shuttle guides.

The shuttles 26 are adapted to be selectively raised by a lifter rod 41, there being one of these rods for each group of three shuttles as clearly seen in Fig. 1. By longitudinal movement of the batten frame 10 in proper sequence according to the controlling mechanism, each shuttle is positioned at the right time directly above the lifter rod 41 which is then raised and engages the padded shoulder 30 of the shuttle 26 below which it is then located, to raise the shuttle and lift it upwardly into the upper shuttle guide and past the latch 29 which then engages the raised shuttle under its shoulder 30 to hold it in such elevated position until it is caused to descend by gravity upon retraction of the latch 29 at the proper moment. The lifter rod 41 is moved upwardly, as above described, through a passage 42 extending through the beam 1, the upper end of the rod passing through the aligned apertures 43 in the plate 38 and padding 39 at the bottom of the lower shuttle guide, to thus reach and engage against the padded shoulder 30 on the shuttle and raise the shuttle.

The lower end of each of the lifter rods is provided with a disk-like head 44 maintained under a bracket 45 secured on top of the lifter bar 46. Said bar 46 is raised and lowered by means of the bell-crank levers 47 and 48 (Fig. 1). Lever 47 is pivoted at 49 at the end of a downwardly extending bar 50, said bar being secured to and extending downwardly from the beam 1. The arm 51 of the lever 47 is pivotally connected to the bar 46, as indicated at 52. A third arm 53 on lever 47 has its end pivotally attached at 54a to the rod 54 which is raised and lowered by suitable cam or other means.

The lever 47 is connected to the lever 48 by means of a connecting rod 55, and the rod 48 has its lower arm 56 pivotally attached at 57 to the lifter bar 46. Lever 48 is pivoted at 58 in the end of a bar 59 secured to and extending downwardly from the beam 1 as clearly seen in Fig. 1. This arrangement is such that a downward pull

exerted on the rod 54 will swing the levers 47 and 48 in such a manner as to cause the bar 46 to be lifted upwardly, this raising the several lifter rods 41 and causing them to raise the shuttles then located above them and to bring the shuttles to their elevated position where they will be held by the latches 29 until they are required to descend and carry their weft threads across the warp.

Behind the batten frame 10 is a frame-work 10 that is fixed to and is carried by the beam 1 and on which the batten frame 10 is slidably mounted. Said frame-work includes a plurality of uprights or vertical bars 60, (Fig. 7) and between pairs of these uprights the reeds 9 are supported. The uprights 60 are attached at the back of the beam 1 by the screws 61 and directly above the beam 1 each pair of the uprights is connected by a rail 62 on which a grooved bar 63, secured to the back of the batten frame 10 by the screws 64, is slideable. The uprights 60 are also connected at their tops by the upper rail 65 secured to said uprights by the screws 66, and a grooved guide bar 67 secured at the back of the top bar 21 of the batten frame 10 by the screws 68 is slideable on the rail 65. Through the arrangement described, it will be noted that the batten frame 10 is longitudinally slideable along the beam 1, being supported thereon on the rollers 19 and being guided on the frame-work secured to the beam, by the engagement of the grooved bars 63 with rails 65 and the engagement of the lower grooved bars 63 with the lower rail 62. The frame-work, including the uprights 60, includes longitudinally extending cross bars 69 which serve to strengthen the frame-work structure. At the top, the several uprights 60 are provided with bearings 70 in which a rocking shaft 71 is mounted. For each group of three shuttles, the shaft 71 carries a finger 72 arranged to be positioned in front of an upstanding part 73a on any one of the latches 29 in each group of shuttles. That is to say, the arrangement is such that when a shuttle is raised and is held in elevated position by one of the latches, the movement of the batten is so timed that when required it will position that shuttle in front of the finger 72 and when the pattern requires the insertion of a weft thread of the color carried by that particular shuttle the rocking shaft 71 will be turned and finger 72 will then draw back the latch 29 and allow the shuttle to drop by gravity and carry the weft thread across the warp.

For causing the required rocking movement of the shaft 71, a tripping member or finger 73 is provided, said finger being attached at one end of the rocking shaft 71 and being provided with a spring 74 (Fig. 2), which normally holds the shaft 71 with its finger 72 extended forwardly and away from the latch behind it. Disposed behind the upstanding finger or tripping member 73 is a bar 75 (Fig. 2), provided at its lower end with a laterally projecting pin 76. At the proper time in the operation of the loom when the descent of a raised shuttle is required, the batten is swung backward, or toward the right as viewed in Fig. 2, and this movement of the batten brings the tripping member or finger 73 in contact with the pin 76. This will cause shaft 71 to be rocked in its bearings 70 and the finger 72 will be swung to retract the latch 29 with which it is in registration, and the shuttle which is then being held in elevated position by the latch so released will descend by gravity and carry the weft thread across the warp. The bar 75 is mounted for vertical sliding move-

ment in guides 77 and 78 secured on a portion 79 of the frame of the loom and this sliding bar 75 is adapted to be raised and lowered at the proper time by means of an arm 80 pivoted at 81 to the frame member 79. The arm 80 is adapted to be raised and lowered as required by suitably timed mechanism and when it is raised it engages under a pin 82 projecting from the sliding bar 75 and it lifts said bar and thus elevates the pin 76 thereon out of the path of the tripping member or finger 73. Accordingly, at times when the batten swings rearwardly, or toward the right as viewed in Fig. 2 and during that movement in the weaving of the fabric, a shuttle is not to be dropped, the bar 75 is then held in elevated position by the arm 80 so that the tripping member or finger 73 will then clear the pin 76 and thus the shuttle will not be released.

The heddles for the loom are shown at 85 in Fig. 3, the details of one of the heddles being made clear in Figs. 4 and 5. It will be therein seen that each heddle consists of a flat tape 86, secured at its ends to the wires 87 and 88. Each heddle is provided with a guide loop 89 through which the warp threads 40 pass. It will be observed that the bank of heddles is so arranged that the warp threads are disposed above one another with the result that the plane of the woven fabric, a portion of which is shown at 90 in Fig. 2 is disposed vertically as distinguished from the usual horizontal disposition of the faces or planes of the fabric in conventional weaving practice. The wires 87 and 88 at the opposite ends of the heddles are carried below rollers 91 at the opposite ends of the loom, which wires thence extend upward into the usual Jacquard loom mechanism. As is well understood, through such mechanism, the heddles are moved to cause the warp threads engaged by them to be drawn aside as required by the pattern to permit of the selective insertion of the weft threads by the required shuttles.

From the foregoing, the operation of the improved loom mechanism will be readily understood. In the form of apparatus disclosed, five fabrics of the same pattern can be woven, but it will be understood that by the employment of a longer batten and an increased number of shuttle gangs, the number of pieces being simultaneously woven can be increased. As the heddles shift the warp threads according to the jacquard pattern to be produced, the change-motion mechanism of the loom will selectively raise the shuttles in their guides and permit the required descent of the raised shuttles by gravity, and on the forward swing of the batten, the reed 9 will pack the inserted weft threads in the shed 91 of the fabric. It will, of course, be understood that the several mechanisms are timed for proper sequence so that the resultant fabric will be woven according to the pattern of the jacquard card arrangement.

To facilitate the roll-up of the woven fabric as it leaves the loom, the fabric is shifted from a vertical position to a horizontal one. This is done by means of a wire guide loop 95 through which the woven fabric is passed and is guided flatwise over a bar 96 and then drawn downwardly to be wound up in a roll by a suitable take-up means of conventional form.

While I have herein shown a single embodiment of the invention, it is obvious that various modifications may be made in the same without departing from the spirit of the invention. The number of pieces woven simultaneously may be increased or decreased; the number of shuttles in each gang might also be changed and the elements of the

described mechanism might be changed in shape and design, all of which can be done without departing from the scope of the invention as expressed in the claims appended hereto.

5. What I claim is:

1. In a loom, a beam on which a batten is longitudinally slidable, shuttle guides mounted on the batten, shuttles slideable in said guides in a vertical direction and transversely of the batten, means located below the guides for selectively engaging the shuttles and raising the same to the top of the guides, means adjacent the tops of the guides for engaging the raised shuttles and holding the same in their raised position, and release means for selectively freeing the shuttles to thereby allow the same to descend solely by gravity in their guides.
2. In a loom, a batten provided with shuttle guideways arranged for the vertical sliding movement of shuttles, a shuttle-elevating device comprising a push-rod located below the guide-ways, means for shifting the batten to thereby selectively position any one of the shuttles directly over the push-rod whereby said rod will, upon rising movement elevate said shuttle in its guideway and means in each guideway for releaseably engaging each shuttle when it is elevated by the push-rod.
3. In a loom, a batten and means for moving the same, a shuttle guide carried by the batten, a shuttle slidably mounted therein for vertical movement, a latch in the shuttle guide for engaging the shuttle when the shuttle is at the top of the guide, lifter means for engaging the shuttle when the same is at the lower portion of the guide to thereby raise the shuttle to a position where the same is engaged and held by the latch, and latch-releasing means independent of the shuttle for engaging the latch and releasing the same to cause the shuttle to descend in its guide solely by gravity.
4. In a loom, a batten, a supporting beam on which the batten is slidably mounted, upper and lower shuttle guides secured to the batten, a shuttle in each of the guides adapted to be vertically raised and lowered therein, a lifter member disposed below the guides, means for shifting the batten along the beam to position any selected one of the shuttle guides above the upper end of the lifter member whereby said lifter member will, upon its ascent, raise the shuttle in said guide, latch means in each of the upper shuttle guides for engaging and holding each shuttle as it is raised in said guide by the lifter member, and latch release means for releasing any selected latch to allow the shuttle held thereby to descend by gravity to reach and enter the lower shuttle guide.
5. In a loom as provided for in claim 4, including heddles for guiding warp threads one above the other and in position to permit insertion of weft threads by the vertically movable shuttles as the same are moved up and down in the shuttle guides.
6. In a loom, a batten including a beam extending transversely of the loom, means for swinging said beam to and from the front of the loom, a batten frame mounted on top of the beam and capable of sliding reciprocating movement thereon, a fixed structure on the beam for guiding the batten frame, a reed carried by the fixed structure, a shuttle guide mounted on the batten frame, shuttles slideably mounted in the guide and capable of vertical sliding movement therein, latches at the upper end of the guide

for engaging the shuttles and holding the same in raised position, latch-release means carried by the fixed structure, means for engaging said latch-release means on the rearward swing of the beam to render said latch-release means effective to release the latches and allow gravitational descent of the shuttles, and means carried by the beam for selectively raising the shuttles in the guide.

7. In a loom, a beam mounted for swinging movement, a batten frame mounted for limited longitudinal sliding movement on the beam, a plurality of shuttles mounted on the batten for vertical ascent and descent thereon and arranged thereon in groups, guide means for the shuttles, means for selectively raising one or the other of the shuttles in each group in said guide means, means for retaining the shuttles in raised position in the guide means, and means for selectively freeing the shuttles-retaining means to thereby allow the shuttles to drop by gravity.

8. In a loom for weaving narrow fabrics, a plurality of horizontally disposed heddles for engaging a plurality of warp threads arranged in superimposed relation, a batten carrying a plurality of shuttles arranged for vertical movement to carry weft threads across the warp threads to thereby produce a woven fabric having its plane surface disposed vertically while being woven, means for moving the shuttles vertically consisting in a plurality of vertically disposed lifter elements positioned below the shuttles, means for simultaneously elevating said lifter elements, means for shifting the batten horizontally to thereby position selected shuttles above the lifter elements, whereby the lifter elements will upon their raising movement elevate selected shuttles only, means for engaging and holding the raised shuttles in their elevated position, and means for selectively causing gravitational descent of the raised shuttles.

9. In a loom of the character described, a plurality of horizontally disposed heddles for supporting a plurality of warp threads in superimposed relation, a batten carrying a plurality of vertically slideable shuttles, guides for said shuttles, means for elevating selected shuttles in their guides, means for holding the shuttles when the same are raised, releasing means for allowing said shuttles to descend by gravity and carry weft threads across the warp threads, a reed carried by the batten for packing the weft threads in the shed while the plane of the woven fabric is vertically disposed, and guide means for guiding the woven fabric to a position wherein its plane is horizontally disposed to facilitate wind-up of the woven fabric.

10. In a loom of the character described, a batten carrying a plurality of shuttles arranged for vertical ascent and descent, a lifter located below the shuttles, means for raising and lowering the lifter, means for shifting the batten in a direction transverse to the direction of ascent and descent of the shuttles whereby any selected shuttles can be positioned above the lifter to thereby cause the lifter to raise said selected shuttle, means for holding the raised shuttle in its elevated position and means for freeing said shuttle-holding means to thereby allow the raised shuttle to descend by gravity.
